PUFFED TEXTILE FABRIC

Charles A. Rudolph, Cornelia, Ga., assignor to Chicopee Mills, Inc., a corporation of New York

Application April 22, 1954, Serial No. 30,132

Term of patent 14 years

(Cl. D92—1)

To all whom it may concern:

Be it known that I, Charles A. Rudolph, a citizen of the United States, residing at Cornelia, in the county of Habersham, State of Georgia, have invented a new, original, and ornamental Design for a Puffed Textile Fabric, of which the following is a specification, reference being had to the accompanying drawing, forming a part thereof, wherein the figure is a plan view of a puffed textile fabric showing my new design.

I claim:

The ornamental design for a puffed textile fabric, as shown.
